FRUIT SLICER WITH STATIONARY KNIVES
AND RECIPROCATING PLUNGER

Vincent Marasco, Los Angeles, Calif.

Application August 26, 1946, Serial No. 693,066

5 Claims. (Cl. 146—169)

1

The present invention relates to slicing machines of the type adapted to slice fruit, and particularly to machines for slicing lemons and similar fruits.

Huge numbers of lemons are used every day in hotels and restaurants as garnishment and as seasoning for sea foods and drinks, especially tea, and the like. Often the lemons are cut transversely and served as rings; but it is generally preferable from the viewpoint of the customer, who is the user, to cut the lemon in longitudinal sections. The latter type of cutting is relatively expensive, because of the time required when the segments are each cut by hand, and therefore not favored by the proprietors. An inexpensive slicing machine can provide the best type of cut at less expense to owners of eating establishments, thus satisfying the needs of all concerned.

Hence it is a general object of my invention to provide a simple and inexpensive slicer for lemons adapted to slice them lengthwise.

Also an object of my invention is to provide for ease of operation of such a slicer by progressive entry of the knives into the skin and the seed zone, which are the zones of hardest cutting.

A further object is to provide a slicer that is simple in construction and easy to assemble and disassemble for cleaning, sterilization, and replacement of the knives.

These and other objects are attained by providing a slicer comprising an upright frame member on which is mounted a plurality of radial blades extending outwardly from a common axis of intersection. The blades are preferably equiangularly spaced, with their cutting edges facing upward. In the preferred embodiment of my invention described herein, the blades are made in pairs in the form of diametral knives which intersect at their mid-point at the common vertical axis. I prefer to provide three such knives; but a different number may be used as desired.

The knives are arranged to commence slicing the lemon at successive positions as it travels along said common axis past the knives. For this purpose the knives are arranged with the inner ends of their cutting edges, and also the major portion of their edges, at different heights. In a preferred form of my invention, these cutting edges all start from substantially the same radius and height and slope downwardly and inwardly to the central point of intersection, but the average slope of each pair of edges is different, and increases progressively in order that the edges start cutting in succession at short intervals.

The edges of all blades may be straight; but in a preferred form the highest pair is concave slightly so that for a short distance in from the ends of the knives, four blades are at about the same height. This construction provides four

2

points of initial contact with the lemon and holds it steady while it is being pushed onto the knives.

A follower is provided with a prong for each space between two blades. By manually operating this follower the operator can push one lemon past the knives. A spring is preferably provided to return the follower to raised position.

I show and describe a preferred form of my invention designed to slice lemons; but it will be understood I am not limited thereto, since other fruit can be sliced without changing the essential features of the invention.

How the above objects and advantages of my invention, as well as others not mentioned, are attained will be more readily understood from reference to the following specification and the annexed drawings, in which:

Fig. 1 is a front elevation of a slicer constructed according to my invention, with a portion broken away to show the knives;

Fig. 2 is a vertical section in line 2—2 of Fig. 1;

Fig. 3 is a fragmentary plan on line 3—3 of Fig. 2 showing the knives and their mounting;

Fig. 4 is a side elevation of one knife;

Fig. 5 is a diagrammatic view showing the top knife in elevation and the profiles of the other two knives in the same plane;

Fig. 6 is a view similar to Fig. 5 of a modified form of knives; and

Fig. 7 is a view similar to Fig. 6 showing another modification in the form of the knives.

Referring now to Figs. 1 and 2 it will be seen that the frame, designated generally at 10, comprises hollow upright 12 attached at its lower end to base 14 which preferably has several feet 15. Base 14 is made arcuate in shape in order that a dish, not shown, to receive the lemon slices can be placed directly under the slicing knives and rest upon the surface 16 supporting base 14 rather than on the base itself.

Near the top, upright 12 has on one face two integral brackets 17 provided with T-shaped slots open at their top sides. These two slots each slidably receive a T-shaped lug 18 on cylindrical housing 20 which supports and encloses the assembly of slicing knives 21, 22 and 23. The housing and knife assembly are held in place by gravity and slicing pressure; but may be easily removed from upright 12 by lifting the housing to raise lugs 18 out of engagement with brackets 17.

The middle knife 22 is shown in elevation in Fig. 4. It, like knives 21 and 23 is shaped with vertical, parallel sides spaced slightly less than the internal diameter of housing 20. At the upper end of each side is a projecting lug 25. Lugs 25 of the knife blades fit into slots 27 in the top edge of housing 20 to hold the knives in position. The width of lugs 25 is preferably no greater than the thickness of the housing wall.

3

Each of the knives 21, 22 and 23 is provided with a pair of cutting edges 21a, 22a, and 23a, respectively. As shown in Fig. 4, edges 22a are arranged in a V-shape; and the other knives are similarly formed. But as shown in Fig. 5, the average slope of each of the pairs of edges 21a, 22a, and 23a, i. e. the cutting edges on each knife, is different and is progressively greater or steeper on the various blades in the sequence 21, 22 and 23. Likewise, in the same sequence, the blades are longer. This permits the blades to cross one another at the center of the blades, which lies on the vertical axis of housing 20. The cutting edges thus slope downwardly and inwardly to the axis of intersection at the center of the knife assembly and housing 20. The tops of the knives when in cutting position in housing 20 (see Figs. 1 and 2), are all at substantially the same level, the top of housing 20. Thus the downward slope of each cutting edge starts from substantially this same level.

To assemble the knives, bottom blade 23 is first dropped into housing 20 and its lugs 25 positioned in two diametrically opposite slots 27. Next intermediate blade 22 is dropped into housing 20, and positioned by two other slots 27. Blade 22 has a notch 30 at the center of its bottom edge in a position to fit over the lowest point of the V between cutting edges 23a. This interlock of the two knives hold their lower ends in position. Finally, the top knife 21 is dropped into place, and positioned by the remaining two slots 27. The top knife has a notch 31, similar to notch 30, which receives knife 22 at their intersection and so interlocks the top and middle knives at their intersection. All three knives now occupy different diametral positions relative to each other and to the axis of housing 20, and are held firmly in position by engagement with each other and with the housing walls. Each half of a knife with its separate cutting edge forms, in effect, a radial blade intersecting the others on the axis of housing 20. When assembling is finished, annular cap 35 is placed on housing 20 over lugs 25 to keep the knife blades in slots 27. Since cutting pressure tends to seat the knives in housing 20, no additional locking means is required; and the knives can be quickly and easily removed from housing 20 for cleaning or replacement by reversing the assembly operation just described.

The angular spacing between the knives can be any desired; but it is preferred that the angular spacing be equal, or substantially so, to produce lemon slices all the same size. As shown best in Fig. 3, the spacing between successive cutting edges is 60°, but a different number of blades may be used in which case the spacing will be greater or less than 60°.

The cutting edges of the knives face upwardly, and the lemon is pushed downwardly past the knives in order to slice it. For this purpose, a manually operated follower is slidably mounted on upright 12 of the frame. This follower comprises a post 37 which slides vertically within hollow upright 12. The two members are preferably square, or some shape other than round, to prevent relative rotation. At the top of post 37 is a cross-head 38 from which a plurality of prongs 40 depend. One prong is provided for each space between two cutting edges, i. e., one for each slice of lemon, six in this instance, as shown in Fig. 3.

A knob 41 is provided on top of cross-head 38. The operator can grasp knob 41 to push

4

down the cross-head and prongs 40 for the purpose of forcing a lemon, shown in dot-dash lines at L in Fig. 1 past the assembly of cutting knives.

The follower means is normally held in the elevated position illustrated in Fig. 2 by spring 43, or some similar means, as in this position the lemon can be readily inserted through the opening in cap 35 and placed on the cutting knives. Spring 43 compresses when the operator pushes down on knob 41, and post 37 telescopes within upright 12. Cross-head 38 can move downwardly to the dot-dash position of Fig. 2, its length of travel and the length of prongs 40 being such that the lemon slices are forced clear of the knives. When knob 41 is released, spring 43 restores the follower to its elevated position.

The profiles of the several cutting edges are illustrated comparatively in Fig. 5, as the drawing shows the knives superimposed one on another. From Fig. 5 it will be seen that the two lower pairs of cutting edges 22a and 23a are substantially straight. For these blades, this shape is preferred since a straight cutting edge slices a lemon effectively and is the simplest shape of edge to grind. The third or top pair of cutting edges 21a is slightly concave. The reason for this slight curvature of one pair will now be explained.

As noted above, all of the cutting edges slope downwardly from points which are substantially at the same level and the same radius outwardly from the axis of the blade assembly. These points are at the top of the blades and beyond the normal radius of a lemon being sliced, as may be seen in Fig. 5. If all blades had straight edges, when a lemon is first placed on the knives it would engage only the top two cutting edges since, because of its rounded shape, it initially engages the cutting edges at a point below and inward of their top ends. However, by providing a slightly concave curvature to the top blades, cutting edges 21a and cutting edges 22a are tangent near their upper ends at or near the point of initial contact of the lemon with these blades. As a result, the lemon initially engages four blades, rather than two, as illustrated in Fig. 5 and is held firmly by this initial engagement against twisting and rocking on the blades during the initial travel of the lemon past the cutting edges. This point or zone of tangency of the two pairs of cutting edges, is located as closely as possible at the average point of initial engagement of the lemon with the knives.

Obviously, this point of tangency can vary somewhat in exact location but it should be located within the range of approximately .6 to .9 of the mean radius of the lemon being sliced.

The reason for providing the variation of average slope will now be explained. The greatest resistance to cutting, as a lemon is moved longitudinally past the knives, is encountered in two different zones. The first zone is the relatively thick rind of the lemon at its lower end. The second zone is at the center of the lemon where the seeds are located. In order to distribute the cutting load relatively evenly over the entire travel of prongs 40, it is desirable that the cutting edges successively enter the zone of relatively high cutting resistance. Progressive entry into these zones distributes the work of cutting more evenly over the entire travel of the lemon, with the result that the force required to push a lemon past the knives is reduced and is more uniform than if all blades entered the zones of high cutting resistance at the same time.

This improved slicing action can be secured by a construction that places the cutting edges at different heights or at successive positions along the path of travel of the lemon. However, for simplicity of construction, I prefer to have the peripheral ends of the cutting edges at, or substantially at, the same elevation. Hence, in a preferred construction the blades slope downwardly and inwardly to their intersection from points at the same level; but the average slope of each diametrically opposed pair of blades, i. e., each knife, differs so that the cutting edges intersect the common axis at different heights. The major portion of the active cutting length of each pair of blades is thus at a different height than that of the other pairs and are engaged in succession by the lemon as it is moved past the knives.

For the above reasons, the difference in average slopes between the several pairs of cutting edges should bear some predetermined relation to the thickness of the thickness of the lemon rind. With the profiles illustrated in Fig. 5, the cutting edges are vertically separated at their midpoints by approximately the average thickness of the lemon rind. This spacing is preferred, but obviously it can varied.

Fig. 6 illustrates a variational shape of the profiles of the cutting edges. In Fig. 6 blades 21, 22 and 23 are provided with upwardly disposed cutting edges 21b, 22b, and 23b, respectively. As before, two pairs of cutting edges are straight; but in this instance it is the top and bottom pairs. One pair of cutting edges is again slightly curved; but in this form the intermediate cutting edges 22b are slightly convex. Otherwise the construction is the same as previously described.

With the profiles illustrated in Fig. 6, it will be seen that the top two pairs of cutting edges 21b and 22b provide a point or zone of tangency within the range previously specified, and consequently a lemon laid upon these cutting edges also initially engages the knives at four points with the same advantageous results as mentioned above.

Fig. 7 illustrates another modification in the profiles of the knives 21, 22 and 23. In this form, cutting edges 21c and 22c have the same profile as edges 21b and 22b in Fig. 6; but it is equally possible to use the outlines of edges 21a and 22a in Fig. 5. The two lowest cutting edges 23c have been modified by lowering the topmost point of each cutting edge so that it starts at a lower point than do edges 21c and 22c. Thus the average slope of edges 23c may be substantially the same as the average slope of edges 22c. This construction requires that the internal diameter of housing 20 and the overall width of the three knives be somewhat increased in order that the net cutting length of blades 23c be the same as before. It will be noted that the modification shown in Fig. 7 is otherwise constructed the same as previously described, and that the cutting edges of the three knives intersect the vertical common axis of the blade assembly at successive points along the axis in the direction of travel of the lemon being sliced.

Having described a preferred embodiment and certain variations of my invention, it will be understood that various changes and construction and design thereof may be made without departing from the spirit and scope of my invention; and consequently, I wish it to be understood that the foregoing description is to be construed as

illustrative of, rather than restrictive upon, the appended claims.

I claim:

- 5 1. In a citrus fruit slicer, the combination comprising: a frame; a plurality in excess of two of angularly spaced diametral knives mounted on the frame and intersecting it at a common axis, each of said knives having a pair of upwardly disposed cutting edges and all cutting edges sloping downwardly and inwardly from substantially the same level with a different average slope for each pair of edges to intersect the common axis at successive points along the axis, the uppermost pair of cutting edges being slightly concave and the next lower pair of cutting edges being substantially straight.
- 10 2. In a citrus fruit slicer, the combination comprising: a frame; a plurality in excess of two of angularly spaced diametral knives mounted on the frame and intersecting it at a common axis, each of said knives having a pair of upwardly disposed cutting edges and all cutting edges sloping downwardly and inwardly from substantially the same level with a different average slope for each pair of edges to intersect the common axis at successive points along the axis, the uppermost pair of cutting edges being substantially straight and the next lower pair of cutting edges being slightly convex.
- 15 3. In a citrus fruit slicer, the combination comprising: a frame; a vertically extending knife housing carried on the frame and having top and bottom openings; and a plurality in excess of two of substantially vertical substantially flat knives mounted in the housing, extending thereacross in angularly spaced relation, and intersecting a common substantially vertical line passing through the housing, each of said knives having a continuous upwardly exposed cutting edge, said cutting edges intersecting said line at spaced points therealong with the portions of said cutting edges on opposite sides of said line extending upwardly and outwardly towards said housing to form a plurality of generally V-shaped cutting edges having different average slopes, the uppermost two of said knives having opposed cutting edge portions shaped to establish four points of initial contact with the fruit.
- 20 4. A citrus fruit slicer as in claim 3 having three knives, the uppermost knife having opposed cutting edge portions that are slightly concave cooperating with the opposed cutting edge portions of the knife next below to establish four points of initial contacts with the fruit.
- 25 5. A citrus fruit slicer as in claim 3 having three knives, the next to the uppermost knife having opposed cutting edge portions that are slightly convex cooperating with the opposed cutting edge portions of the uppermost knife to establish four points of initial contact for the fruit.
